CLAIM

The ornamental design for an electric massaging chair, as shown and described.

DESCRIPTION

FIG. 1 is a perspective view of the design for an electric massaging chair according to the invention.

FIG. 2 is a front view of the design according to the invention. A rear view of the design according to the invention is a mirror image of the front view as shown in FIG. 2.

FIG. 3 is a right side view of the design according to the invention.

FIG. 4 is a left side view of the design according to the invention.

FIG. 5 is a top view of the design according to the invention.

FIG. 6 is a bottom view of the design according to the invention.

FIG. 7 is a sectional view of the design along the line 7—7, which shifts at the center line, in FIG. 6 according to the invention, where the internal components are omitted; and, FIG. 8 is a reference view showing that the electric massaging chair is reclined.

The elements shown in broken lines are for illustrative purposes only and form no part of the claimed invention.
